UNITED STATES PATENT OFFICE.

RICHARD WEBER, OF DRESDEN-UEBIGAU, GERMANY.

PROCESS OF PRODUCING BASKETS AND OTHER BASKETWORK STRUCTURES.

Application filed October 31, 1927. Serial No. 230,129.

The present invention relates to a process of producing baskets and other basket work structures, the new process being adapted to produce in the simplest possible manner both 5 angular and round baskets. The weaving need not be done by a trained basket-maker, yet the accuracy and rigidity of the finished products is remarkable. The former art knows processes of producing baskets employing a perforated base plate on which a perforated bottom is placed, whereupon stakes are run through the holes in the bottom and into the holes of the base plate, the walls of the basket woven, and the ends of the 10 stakes projecting beyond the bottom are interwoven to form a rim. Under this process only willow or cane products could be manufactured while the present invention makes it possible to produce baskets, in 15 which the vertical stakes can be made of metal, to impart greater rigidity to the baskets. The stakes pass through the entire height of the basket and are clamped about the top filler strand and the end strand below the bottom. At the same time, the ends 20 of the stakes projecting beyond the bottom may be connected by weaving filler strands in 25 between them.

One form of the invention is shown in the 30 accompanying illustrations, in which Fig. 1 is a perspective view of a finished basket; Fig. 2, a longitudinal section of a basket from corner to corner; Fig. 3, a top view of a device applying the process; Fig. 4, a section 35 on the line 3-3, Fig. 3; Fig. 5, a section of the fastening device, and Fig. 6, a frame of the type used for making round baskets.

1 are the corner stakes of the basket and attached to the bottom 3 consisting of a perforated base plate by means of the flexible angles 2. 4 are ledges which may be arranged underneath the bottom 3 and secured by means of the screw bolts 5. The walls of the basket consist of the vertical stakes 6 and 45 the longitudinal strands 6^a. 7 is the foot of the basket formed underneath the bottom 3. 8 are the handles.

In the manufacture of the basket a base plate 9 is employed and can be rotated about 50 a vertical shaft 10. The base plate 9 is provided with adjustable holes 11. 12 is a frame provided with a plurality of perforations 13. The corners have larger perforations 14 for the reception of the corner stakes 1. 55 The frame 12 is placed on the base plate 9

and secured to the latter by means of the angles 15 run through the holes 11 of the base plate. 16 are thumb screws for tightening the holding angles 15 to prevent them from projecting beyond the frame and make 60 it possible to place the bottom 3 perfectly flat on the frame. The bottom 3 is provided with suitable perforations for the reception of the stakes, and after the bottom has been placed on the frame 12 the stakes 6 are inserted in the holes of the bottom 3 and also in any suitable hole 13 of the frame 12, the corner stakes 1 being inserted in the holes 14 (Fig. 4). The stakes are then connected 65 by weaving in horizontal strands 6^a. After 70 the walls are finished they are removed from the frame 12 and the base plate 9 together with the bottom 3, and the ends of the stakes previously inserted in the holes 13 and projecting beyond the bottom 3 are connected by 75 weaving in horizontal strands 6^a and clamping the ends about the last horizontal strand so as to produce the foot 7.

When making round baskets the corner stakes are dispensed with, a round frame provided with a plurality of holes being employed in that case (Fig. 6).

I claim:—

1. The process of producing baskets and other basket work structures, in which a bottom is placed on a rotatable base plate, stakes are run through the said bottom and the base plate is removed after weaving the walls of the basket, consisting in securing in a suitable manner to a base plate a frame provided 85 with a plurality of holes for the reception of the stakes, in placing the bottom on the frame and inserting the said stakes through the bottom in the holes of the frame until they strike the base plate, and in connecting the 90 ends of the stakes projecting beyond the bottom after removing the frame by weaving in longitudinal strands and clamping the said ends about the last strand.

2. The process of producing baskets and other basket work structures consisting in placing on a base plate having a plurality of adjustable holes a frame provided with a large number of holes arranged at will, in running angles through the said adjustable 105 holes for fastening the frame, in placing a firm bottom provided with holes on the said frame and passing the stakes through the holes of the frame until they strike the base plate, in weaving the wall of the basket above 110

the bottom, removing the frame and base plate after weaving and in connecting the ends of the stakes projecting beyond the bottom by weaving in longitudinal strands between them.

3. The process of producing baskets and other basket work structures according to

claim 1 consisting in employing a frame provided with larger perforations in its corners for receiving the corner posts during the manufacture of angular baskets.

In testimony whereof I have affixed my signature.

RICHARD WEBER.
